UNITED STATES PATENT OFFICE.

HORACE E. HENWOOD, OF KANSAS CITY, MISSOURI, ASSIGNOR TO HIMSELF
AND JERE. H. CHAMBERLAIN, OF SAME PLACE.

GOLD-SEPARATOR.

SPECIFICATION forming part of Letters Patent No. 245,165, dated August 2, 1881.

Application filed April 28, 1881. (No model.)

To all whom it may concern:

Be it known that I, HORACE EDWIN HENWOOD, residing at Kansas City, in the county of Jackson and State of Missouri, have invented a new and useful Improvement in Gold-Separators, of which the following is a full, clear, and exact description, reference being had to the accompanying drawings, forming part of this specification.

10 My invention relates to gold-separators in which gold is extracted from sand by means of the centrifugal force generated by a revolving hopper; and it consists in certain peculiarities of construction, as hereinafter described.

15 In the accompanying drawings, Figure 1 represents a vertical central section, and Fig. 2 a plan view.

20 In constructing my improved separator, instead of using the heretofore-employed revolving hopper having radial arms, I adopt a cylindrical hopper, A, as being less liable to spill the sand and necessitate repeated handling of the same. This hopper is made open at both ends, and provided at the lower end with an internal annular trough, B, whose outer wall is formed by the said cylinder. The said trough is partially closed at the top by a circular flange, b, which is attached to the top of its inner wall and inclined upward toward the 25 outer wall. The upper rim of the cylindrical hopper is curved inward to prevent the sand from falling into the trough while being poured upon the circular distributor C, and also to prevent the escape of the quicksilver. This distributor is provided with radial corrugations or channels for conveying the sand more evenly against the wall of the cylinder, and is secured to the hopper by means of the socket D, which receives the vertical shaft of the support E. 30 At the lower end of this socket is secured a pulley, F, for communicating motion to the machine.

35 The trough B is designed for holding quicksilver, which will flow up the wall of the cylinder as the latter is rapidly revolved and unite with the gold, which, from its greater weight, will be thrown into the trough, while the sand, falling upon the flange b, will slide downward and out at the bottom of the hopper. By this means the sand is easily and quickly discharged, and 40 will be thoroughly separated from the gold. An opening in the bottom of the trough, as shown, is designed for drawing off the quicksilver.

45 Having thus described my invention, what I claim as new, and desire to secure by Letters Patent, is—

1. In a gold-separator employing centrifugal force, the cylindrical hopper A, having its upper edge curved inward and provided at its lower open end with an internal annular 50 trough, B, having a circular inclined flange, b, in combination with a distributor having radial corrugations, substantially as shown and described.

2. In a gold-separator employing centrifugal force, the radially-corrugated distributor C, in combination with the cylindrical hopper A, having annular trough B, whose inner wall is provided with an upward-inclined flange, b, substantially as shown and described. 55

3. In a gold-separator employing centrifugal force, the annular trough B, having its outer wall formed by the cylindrical hopper A and the top of its inner wall provided with an upward-inclined flange, b, whereby the same 60 shall be partially covered, in combination with a suitable distributor, substantially as shown and described. 70

HORACE EDWIN HENWOOD.
